DESIGN FOR A TIME INDICATOR OR THE LIKE

Emory W. Adams, Oakland, Md.

Application July 3, 1945, Serial No. 120,486

Term of patent 3½ years

(Cl. D42—7)

To all whom it may concern:

Be it known that I, Emory W. Adams, a citizen of the United States of America, residing at Oakland, in the county of Garrett and State of Maryland, have invented a new, original, and ornamental Design for a Time Indicator or the Like, of which the following is a specification, reference being had to the accompanying drawing, forming a part thereof.

In the drawing:

Fig. 1 is a front elevational view of a time indicator or the like showing my new design, the rear of the same being plain; and

Fig. 2 is a side elevational view thereof.

I claim:

The ornamental design for a time indicator or the like, as shown and described.

EMORY W. ADAMS.
